Primary Examiner — Karen E Kearney*Assistant Examiner* — John Reickel(74) *Attorney, Agent, or Firm* — Harness, Dickey & Pierce(57) **CLAIM**

We claim the ornamental design for a display screen or portion thereof with graphical user interface, as shown and described.

DESCRIPTION

FIG. 1 is a front view of a display screen or portion thereof with graphical user interface showing our new design; and, FIG. 2 is an enlarged view of a portion of the claim from the right-upper side of FIG. 1, shown separately for ease of illustration.

The broken lines are for environmental purposes only and form no part of the claimed design.
